(57) **CLAIM**

The ornamental design for a digital audio disc player with tuner and television monitor, as shown and described.

DESCRIPTION

FIG. 1 is a perspective view of a digital audio disc player with tuner and television monitor, showing our new, original and ornamental design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is perspective view thereof with the monitor portion inside of the case.

The broken line structure in FIG. 3 is for illustrative purposes only and forms no part of the claimed design.
